[57] CLAIM

The ornamental design for a securing and support device for conduits, pipes, or the like, as shown.

DESCRIPTION

FIG. 1 is a perspective view of a securing and support device for conduits, pipes or the like showing my new design;

FIG. 2 is a top plan view thereof;

FIG. 3 is a front elevational view with the opposite side being a mirror image thereof;

FIG. 4 is an end elevational view of the second embodiment of the design shown in FIG. 1;

FIG. 5 is a bottom plan view thereof;

FIG. 6 is an isometric view of a second embodiment of a securing and support device for conduits, pipes, etc., incorporating my new design;

FIG. 7 is a front elevational view with the opposite end being a mirror image thereof;

FIG. 8 is an end elevational view with the opposite end being a mirror image thereof;

FIG. 9 is a top plan view thereof;

FIG. 10 is a bottom plan view thereof.

FIG. 1.FIG. 2.FIG. 3.FIG. 4.FIG. 5.

*FIG. 6.**FIG. 7.**FIG. 8.**FIG. 9.**FIG. 10.*
